UNITED STATES PATENT OFFICE.

GEORGE J. GOODHUE, OF STEVENS POINT, ASSIGNOR OF ONE-HALF TO
HARVEY M. WADLEIGH, OF HATLEY, WISCONSIN.

WOOD-WORKING MACHINE.

SPECIFICATION forming part of Letters Patent No. 374,671, dated December 13, 1887.

Application filed May 2, 1887. Serial No. 236,830. (No model.)

To all whom it may concern:

Be it known that I, GEORGE J. GOODHUE, of Stevens Point, in the county of Portage, and in the State of Wisconsin, have invented certain new and useful Improvements in Wood-Working Machines; and I do hereby declare that the following is a full, clear, and exact description thereof.

My invention relates to wood-working machines, being specially designed for shaping the ends of the caps that form part of the timber structure for mines, set forth in Letters Patent No. 358,261, dated February 22, 1887; and it consists in certain peculiarities of construction and combination of parts, to be hereinafter described with reference to the accompanying drawings, and subsequently claimed.

In the drawings, Figure 1 represents an elevation of a machine constructed according to my invention; Fig. 2, a vertical transverse section taken on line *xx* of Fig. 1; Fig. 3, a similar view taken on line *yy*, Fig. 2; Fig. 4, a detail view of the dogs and means for adjusting the same, and Fig. 5 an end view of the product of my machine.

Referring by letter to the drawings, A A represent horizontal timbers, each of which is provided with a track, B, for the wheels C of a carriage, D, and to the ends of this carriage are secured guides E for flanged plates F, carrying dogs G. Each of the plates F has bolted or otherwise suitably secured to the under side thereof a screw-threaded bearing, G', for the screw-threaded end of a rod, H, and by referring to Fig. 4 it will be seen that the threads on one end of said rod are opposite to those on the other end thereof.

Fast on the rod, H is a gear-wheel, I, that meshes with a pinion, J', on a shaft, J, mounted on the carriage D and provided with a crank, J², as best illustrated in Fig. 1. The carriage D has secured thereto, on one side thereof, a rack, K, that engages a pinion, L', on a vertical shaft, L, and secured to the upper end of said shaft is a hand-wheel, L². Opposite each end of the carriage D are vertical posts M M, each of which has secured thereto a bearing, N, for a horizontal shaft, O, and to one end of this shaft is fixed a drive-pulley, P.

Mounted on each shaft O, between the posts M M, are cylindrical heads Q Q, carrying a

series of radial saws, a, and a series of longitudinal knives, b, and interposed between said heads is another head, R, carrying knives c, as best illustrated in Fig. 2, the latter head being of much less diameter than the ones Q Q.

The timber to be operated upon is rolled along on skids S to the carriage D, and then raised up to the elevation shown in Fig. 1. The crank J² is now operated to communicate motion to the rod through the medium of the pinion J' and gear-wheel I, and thus the dogs G are caused to approach and engage the ends of said timber, whereby the latter is held in its elevated position.

By operating the hand-wheel L in either direction the carriage D is caused to move toward one pair of the heads Q. The timber comes first into contact with the saws a on the heads, said saws being slightly in advance of the knives b, and thus a cut is made in said timber on each side thereof. The saws being followed by the knives b, that portion of the timber outside said saws is gradually chipped away to leave a tongue, d. Stops T are employed to limit the movement of the carriage D, and just before said carriage and stops come into contact with each other the knives c on the head R come into play to chip out a concave recess, d', in the end of the timber at right angles to the tongue d. When one end of the timber has been completed, a reverse movement is given to the carriage to bring the other end of said timber in contact with the saws and knives on the opposite set of heads, whereby a similar result is obtained. Both ends of the timber having been shaped, the carriage is run back to the position shown in Fig. 1, the dogs released from said timber, and the latter rolled away from the machine.

Having thus fully described my invention, what I claim as new, and desire to secure by Letters Patent, is—

1. In a wood-working machine, the combination of a reciprocative carriage with cylindrical heads arranged in pairs upon a revolvable shaft and provided with radial saws and longitudinal knives, and another cutter-head of less diameter interposed between the first-named heads, substantially as and for the purpose set forth.

2. In a wood-working machine, the combi-

5 nation of a reciprocative carriage, a revoluble shaft arranged opposite each end of the carriage, cylindrical heads arranged in pairs on each shaft and provided with radial saws and longitudinal knives, and another cutter-head of less diameter interposed between the first-named heads, substantially as and for the purpose set forth.

3. In a wood-working machine, the combination of a reciprocating carriage, dogs arranged on the carriage at the ends thereof, a horizontal rod having its ends screw-threaded in opposition to each other and connected to

the dogs, a gear-wheel fast on the rod, a pinion arranged on the carriage to mesh with the gear-wheel, and suitable means for operating the pinion, substantially as set forth.

In testimony that I claim the foregoing I have hereunto set my hand, at Milwaukee, in the county of Milwaukee and State of Wisconsin, 15 20 in the presence of two witnesses.

GEORGE J. GOODHUE.
